UNITED STATES PATENT OFFICE

2,638,185

FRICTION ENGAGING DEVICE AND CONTROL MEANS THEREFOR

Harold E. Carnagua and Donald W. Kelbel, Mun-
cie, Ind., assignors to Borg-Warner Corpora-
tion, Chicago, Ill., a corporation of Illinois

Original application December 16, 1943, Serial No.
514,464. Divided and this application October
31, 1946, Serial No. 706,960

9 Claims. (Cl. 188—151)

1

This invention relates to friction engaging de-
vices and control mechanisms therefor.

It is an object of our invention to provide a
compact arrangement of a plurality of friction-
ally engaging devices and more particularly it
is an object to provide such an arrangement in
which the frictionally engaging devices are hy-
draulically operated.

It is still more particularly an object of the
present invention to provide a hydraulically op-
erating arrangement for a pair of such frictional
devices in which a single piston is used for en-
gaging both of the devices, each to the exclusion
of the other, whereby the two devices are mu-
tually exclusively operable.

This application is a division of our copending
application, Serial No. 514,464, filed December
16, 1943, now Patent No. 2,414,359.

The invention consists of the novel construc-
tions, arrangements and devices to be hereinafter
described and claimed for carrying out the above
stated objects and such other objects as will
appear from the following description of a cer-
tain preferred embodiment which is illustrated
in the accompanying drawing, wherein:

Fig. 1 is an end elevation, partly in section,
of a brake arrangement and control mechanism
therefor embodying the principles of invention,
said section being taken on line 1—1 of Fig. 2;
and

Fig. 2 is a longitudinal sectional view of the
brake arrangement and control mechanism there-
for shown in Fig. 1.

Like characters of reference designate like parts
in the several views.

Referring to the drawing, a pair of friction en-
gaging devices, and control mechanisms therefor,
are illustrated in a preferred embodiment of the
invention as comprising a pair of brakes 18 and
22. Said brakes comprise a cylinder 78 formed
in housing 71 in which is a double acting piston
79. It will be noted that the cylinder 78 is dis-
posed radially of two brake drums 36 and 38
and off their peripheries. The ends of cylinder
78 are closed off by end plates 80 and 81 and re-
silient means such as coil springs 82 and 83 are
compressed between piston 79 and end plates
80 and 81. The pressure of springs 82 and 83
is not taken directly by piston 79 but by aper-
tured stampings or abutments 84 and 85 each of
which is anchored to a piston rod 86 and 87 re-
spectively. The stampings 84 and 85 are annular
in shape and, in the assembly shown, are separate
from the piston 79, the outer peripheries of the
stampings contacting the opposite ends of the

2

piston 79, so that the piston may move relative
to the stampings during the operation of the
brake mechanism as will now be described. The
rods are provided with shoulders 88 and 89, re-
spectively, which limit the inward movement of
the rods, the shoulder 88 on the rod 86 also limit-
ing movement of the stamping 84 to the right
(Fig. 1) and the shoulder 89 also limiting move-
ment of the stamping 85 to the left (Fig. 1).
In order to move one of the rods, for example
rod 87, outward, fluid under pressure is admitted
through a conduit 90 into the opposite half of
cylinder 78 and the fluid then passes through the
apertures 84a in the stamping 84 to piston 79,
thereby forcing the piston to the right as viewed
in Fig. 1 against stamping 85 to move rod 87 out-
ward. A similar arrangement of parts is used
to cause piston rod 86 to be moved to the left
as shown in Fig. 1. More specifically, upon the
release of fluid under pressure acting in the
cylinder to move the stamping 84, movement of
the rod 86 outward may be effected by the admis-
sion of fluid under pressure through a conduit
102 into the other half of the cylinder 78 and the
fluid then passes through the apertures 85a in
the stamping 85 to the piston 79 to force the
piston to the left as viewed in Fig. 1 against
stamping 84 to move rod 86 outward.

The movement of each rod is transmitted to
the respective brakes by suitable linkage. As an
example of one form of linkage, rod 87 is con-
nected through a pin-and-slot connection 91 to a
bell crank 92 which is pivoted at 93 to an anchor
block for a brake band 94. Said brake band 94
cooperates with drum 36 of brake 18. A spring
95 tensioned between housing 71 and a lug 96
on band 94 tends to rotate the end secured there-
to in a counterclockwise direction as viewed in
Fig. 1. The opposite end 97 of brake band 94
is secured to an anchor block 98 which is pivotally
connected at 99 to a tension rod 100, said rod
being pivoted at its opposite end 101 to bell crank
92. It will be apparent from the arrangement
of the various links and anchor blocks that when
piston rod 87 is moved to the right as viewed in
Fig. 1 the ends of the brake band will be drawn
together to effect its tightening about its asso-
ciated drum, thereby causing the brake to become
operative to arrest the rotation of shaft 35. It
will also be observed that spring 83 in cylinder
79 and spring 95 will tend to release the brake.
A similar arrangement may be used to operate
the brake 22.

It will be observed that the operating linkages
of brakes 18 and 22 are of the servo type, thus

requiring less pressure in the operating cylinder. As the brake bands take hold, they will rock around and lock with a greater force than that applied by the oil pressure alone. The arrangement of the piston 79 with the brakes 18 and 22 is quite compact and the arrangement is further advantageous in that the single piston 79 is adapted for operating both of the brakes 18 and 22 mutually exclusively of the other.

It may be noted that passages 70, 76, and 77 for fluid under pressure are shown in Fig. 2, the passages 70, 76 and 77 respectively communicating with clutches and a torque converter of a transmission shown and described in our United States Patent No. 2,414,359. Accordingly, while these passages are shown in Fig. 2, the passages do not communicate with the ports 90 and 102 in Fig. 1 and are not necessary for the operation of the brake mechanism shown in Figs. 1 and 2.

We wish it to be understood that our invention is not to be limited to the specific constructions and arrangements shown and described, except only insofar as the claims may be so limited, as it will be apparent to those skilled in the art that changes may be made without departing from the principles of the invention.

We claim:

1. A control device for a plurality of friction-engaging means including mutually exclusively operable elements disposed exteriorly of said device comprising means forming a chamber, a piston in said chamber, and a pair of piston rods extending into said chamber and adapted to be actuated by said piston, each rod also extending exteriorly of said device and being connected to operate one of said mutually exclusively operable elements, the operative relation between said pistons and piston rods being such that movement of said piston in one direction will actuate one of said elements away from the other and movement of the piston in the opposite direction will actuate the other of said elements away from said one element, and spring means on said rods and urging the rods toward each other.

2. A control device for a plurality of friction-engaging means including mutually exclusively operable elements disposed exteriorly of said device comprising means forming a chamber, a piston in said chamber, a pair of piston rods extending into said chamber, each rod also extending exteriorly of said device and being connected to operate one of said mutually exclusively operable elements, and means for effectively connecting said piston and rods whereby movement of said piston in one direction will actuate one of said rods but not the other and movement in the opposite direction will actuate said last-named rod but not said first-named rod.

3. A control device for friction-engaging means including mutually exclusively operable elements disposed exteriorly of said device comprising a chamber, a piston in said chamber, a pair of piston rods extending into said chamber, each rod also extending exteriorly of said device and being connected to operate one of said mutually exclusively operable elements, and an abutment on each rod in the path of movement of the piston, said piston being urged against one or the other of the abutments, by the establishment of a difference of pressure on the sides of the piston, to move one of said rods but not the other of said rods.

4. A fluid-pressure responsive control device for a plurality of friction-engaging means including mutually exclusively operable elements dis-

posed exteriorly of said device comprising a chamber having end walls in fixed spaced relation, a piston in said chamber, a pair of piston rods extending through said walls and into said chamber, each rod also extending exteriorly of said device and being connected to operate one of said mutually exclusively operable elements, and an abutment on each rod in the path of movement of the piston, said piston being urged against one of said abutments to actuate the corresponding piston rod and element by fluid pressure on one side of the piston and being urged against the other of said abutments to cause movement of the corresponding rod and element by fluid pressure on the other side of the piston.

5. A fluid-pressure responsive control device for a pair of friction-engaging means including mutually exclusively operable elements disposed exteriorly of said device comprising means forming a cylindrical chamber having spaced end walls, a piston in said chamber, a pair of piston rods extending through said walls into said chamber from opposite ends thereof, each rod also extending exteriorly of said device and being connected to operate one of said mutually exclusively operable elements, and an abutment on each rod in the path of movement of said piston, said piston being urged against one of said abutments in one direction to cause a movement of the corresponding rod and element by the establishment of pressure on one side of the piston and being urged against the other of said abutments in the other direction to cause a movement of the corresponding rod and piston by a pressure on the other side of said piston and springs within said chamber and acting against said end walls and said abutments to maintain one of said rods in retracted position and to yieldingly resist movement of the other of said rods by said piston, during movement of said piston.

6. A control device for mutually exclusively operable elements disposed exteriorly of said device comprising means forming a chamber, a piston in said chamber, a pair of piston rods extending into said chamber from opposite ends thereof, each rod also extending exteriorly of said device and being connected to operate one of said mutually exclusively operable elements, an abutment on each rod in the path of movement of said piston, said piston coacting with one of said abutments to cause movement of the corresponding rod when moved in one direction and coacting with the other of said abutments to cause movement of the other rod when moved in the opposite direction, a spring acting between each of said abutments and the adjacent end of said chamber for yieldingly holding the corresponding rod in its inoperative position, and means engaging said rods and spaced walls of said means forming said chamber for limiting movement of each rod into the chamber.

7. A control device for mutually exclusively operable elements disposed exteriorly of said device comprising means forming a chamber, a piston in said chamber, a pair of piston rods extending into said chamber from opposite ends thereof, each rod also extending exteriorly of said device and being connected to operate one of said mutually exclusively operable elements, an abutment on each rod in the path of movement of said piston, said piston being urged against one or the other of said abutments by the establishment of a difference of pressure on the sides of the piston, a spring between each of said abutments and the adjacent end of said chamber for

yieldingly holding the rod in its retracted position, and means on each rod and engageable with spaced walls of said means forming said chamber for limiting the movement of each rod into the chamber.

8. Fluid-pressure responsive control means for two brakes including brake drums which are disposed coaxially and side by side and a band for engaging each of the drums, comprising casing means forming a chamber spaced radially of said drums and disposed off their peripheries, a piston in said chamber, a pair of piston rods extending into said chamber from opposite ends thereof, each of said rods being connected to operate one of said brake bands, and an abutment on each rod in the path of movement of the piston, said piston coacting with one of said abutments when the piston is moved in one direction for thereby actuating the corresponding shift rod and engaging the corresponding brake and similarly engaging the other brake when the piston is moved in the opposite direction, said piston being urged against one or the other of said abutments by the establishment of a difference of pressure on the sides of the piston to move one of the shift rods but not the other of said shift rods.

9. Fluid-pressure responsive control means for a plurality of brakes including brake drums which are disposed coaxially and side by side and a band for engaging each of the drums, comprising casing means forming a chamber spaced

radially of said drums and disposed off their peripheries, a piston in said chamber, a pair of piston rods extending into said chamber from opposite ends thereof, each rod being linked with one of said brake bands for operating the band, and an abutment on each rod in the path of movement of said piston, said piston when moved in one direction engaging one of said abutments and actuating the corresponding rod and brake band and when moved in the opposite direction similarly actuating the other brake band, and a spring disposed between each of said abutments and the adjacent end of said chamber for holding the corresponding piston rod in its retracted position, and means on each rod and engageable with spaced walls of said chamber means for limiting the movement of each rod into the chamber.
